CHILL MEMBER

Matthew G. Sternberg, East Chicago, Ind., assignor to Continental Roll & Steel Foundry Company, East Chicago, Ind., a corporation of Delaware

Application April 17, 1937, Serial No. 137,453

2 Claims. (Cl. 22—174)

The present invention relates to chill members for use in casting large steel and alloy rolls for rolling mills and methods of casting such rolls.

In connection with the manufacture of rolls for rolling mills and particularly rolls of relatively large sizes, that is to say, rolls from 30 inches in diameter and larger, a great deal of difficulty has been experienced in the past from roll breakage resulting from internal stresses and strains within the metal comprising the body of the roll.

It was formerly believed that this breakage was due to improper annealing. The reason the annealing was believed to be at fault was because at the point of breakage the outer layer of metal constituting the roll appeared to have a fine grain structure whereas the metal as it approached the center of the roll would have a coarse grain structure and it was thought that the annealing had merely penetrated a short distance and that the interior of the roll was improperly annealed.

Various attempts have been made in the past to overcome breakage. It has even been suggested that large rolls be formed by making an arbor and sweating a sleeve onto the arbor and thus, in view of the reduced masses of metal to be cast at one time, to eliminate internal stresses and strains.

I have discovered, however, that in the majority of cases the internal stresses and strains in the roll which cause breakage are not due to faulty annealing but rather to the fact that in casting large rolls it is necessary that the metal be poured at relatively low temperatures and after the metal is poured due to the uneven cooling there is set up an internal strain located in the interior thereof which causes the roll to break under rolling stresses. The strains may be so great that there is a crack or fissure formed in the interior of the roll that extends at approximately right angles to the axis thereof. In some cases where the roll breakages are due to defects in the casting of the roll, it is possible to measure the extent of this crack.

The fault is not due to the annealing. It will be found that although the fracture shows a circular band of sound metal at the periphery of the roll and the central area has a different type of structure varying from coarse to very coarse or of the concrete type that if a section is cut directly beneath the fracture the grain structure will vary but slightly and is practically uniform throughout the entire cross section of the roll.

I have discovered that the stresses and strains which cause breakage are due to improper cool-

ing of the roll after being cast and may be eliminated by the use of an internal cooling medium.

To illustrate my invention in more detail, there is shown in the accompany drawing a diagrammatic view of a roll illustrating the manner in which the cooling ordinarily takes place and in the remaining views is shown a preferred form of internal cooling member. It is to be understood, however, that the drawing and the accompanying specification are for purposes of exemplification only and that modifications may be made in the form of cooling medium used and its method of application without departing from the spirit and scope of the invention defined in the appended claims.

In the drawing:

Fig. 1 is a sectional view showing the stages of solidification of a roll as it cools after being poured;

Fig. 2 is a view in elevation showing a preferred form of internal cooling member; and

Fig. 3 is a section taken on the line 3—3 of Fig. 2.

Referring to Fig. 1 of the drawing, it will be observed that the roll is divided into zones which have been identified by the letters A, B, C and D, respectively. In the ordinary cooling of a roll the zone identified by the letter A cools and solidifies first, the metal in the zones B, C and D being still at a high temperature and in an expanded condition after zone A has solidified.

The metal in zone B then solidifies while the metal in zones C and D is still in an expanded and fluid condition. Zone C next solidifies and leaves the final zone D in an expanded fluid condition. As zone D cools and solidifies it also contracts and since the surrounding zones are in solid condition the weight of the metal in zone D tends to pull the top portion of this metal away from zone C as the metal cools at the point indicated in dotted lines and designated as E. It is when the metal reaches a mushy stage that its weight tends to cause such separation to take place thus resulting in a fault or strain in the roll body.

The zones illustrated in Fig. 1 of the drawing are purely illustrative as the zones will vary with different sizes and shapes of rolls but it will be found in general that in a plane body roll the last portion to cool will be in the upper central portion of the roll body and that the strain will take place at this point.

In Figs. 2 and 3 of the drawing I have shown a preferred form of internal cooling member which, when properly applied, will avoid the setting up of internal strains which tend to weaken

the roll and which result in its failure. This member comprises a central steel support 11 which is preferably surrounded by a cage type structure comprising a plurality of short bars 12 and a plurality of long bars 13. The bars 12 are secured to the member 11 by means of supporting arms 14 which may be welded or otherwise attached to the supporting member 11 and the bars 12. Similarly, the long bars 13 are attached to the member 11 by supporting arms 15.

10 The upper end of the supporting member 11 is provided with cross members 16 which are adapted to engage the upper edges of the mold in which the roll is being cast and thus prohibit the cooling member from dropping into the metal beyond the desired point. A ring member 17 is provided at the top of the cooling member so that it may be readily handled by a crane.

15 It will be observed that the short bars 12 are not in position parallel with the member 11 but converge toward their upper end and the long bars 13 converge toward their lower end. As shown in the drawing the inner ends of these bars 12 and 13 may overlap or be interposed between each other. The inner ends of the two sets of bars are so located as to be in the upper half of the body of the roll when it is cast. The object in so arranging the bars is to have them so positioned that they will be most effective in the distribution of heat in that portion of the roll which would normally solidify last, namely, in the zones C and D and particularly D, as illustrated in Fig. 1 because of the formation of more columns of metal at that point by means of the 20 overlapped bars. Of course, with a change in the shape of the roll body it would be necessary to change the general arrangement and size of the bars around the supporting member 11.

25 In the use of this internal cooling medium when casting a large roll for rolling mills I have found that in order for it to be most effective it must be inserted into the cast metal a period of time after the metal has been poured. If the member is placed in the metal too soon it melts and is 30 not effective in the elimination of the strain conditions which it is intended to overcome. It is desirable, however, that the member be inserted in the metal sufficiently soon after pouring so that it fuses.

35 50 When the internal cooling member is inserted in the roll the central supporting member and the outside bars cool the metal immediately adjacent to them and form within the roll a plurality of columns of metal which have some

strength and thus as the roll cools there is no extensive fluid portion which finally cools as a segregated whole. Furthermore, the columns of metal built up within the roll body tend to hold the metal together and prohibit it from separating and causing a fault or a strain.

5 The time of insertion is of importance in order to accomplish this result and while some variation in time is permissible, a rule which may be generally followed is that with a thirty inch diameter plane body roll the cooling member should be inserted at the end of thirty minutes after the metal has been poured and for each inch the diameter of the roll increases there should be one additional minute delay before inserting the cooling member, that is to say, it should be inserted after forty minutes in a forty inch diameter roll, etc.

10 When this type of cooling member is used in rolls having a shaped body, such as rolls used in 20 rolling rails, beams and the like, the time of insertion will vary somewhat from that of a plane body roll depending upon the shape of the roll. In connection with such rolls the general rule is that the member should be inserted a sufficient 25 time after casting so as not to be completely absorbed and a short time prior to solidification of the interior of the roll.

15 I have found that by the use of an internal cooling medium of the type herein described and 30 set forth that internal strains and stresses due to the casting of large rolls for rolling mills are eliminated for all practical purposes and, therefore, breakage from this cause is reduced to a minimum.

35 I claim:

1. A chill member for use in casting large size rolls for rolling mills including a central supporting member, a group of a plurality of bars surrounding and supported by said member adjacent its upper end, a second group of a plurality of bars surrounding and supported by said member adjacent its lower end, both groups of bars running generally longitudinally of said supporting member and converging from the inner 40 ends of said bars towards the outer ends of said supporting member, the bars of the first named group being interposed between the bars of the second named group at their inner ends.

2. A chill member as described in claim 1 and 50 wherein the bars of the first named group are shorter than the bars of the second named group.

MATTHEW G. STERNBERG.
